UNITED STATES PATENT OFFICE.

GERARD JOHAN LUGT, OF AMSTERDAM, NETHERLANDS.

DEVICE FOR SUPPLYING COOLING LIQUIDS TO PISTONS OF INTERNAL-COMBUSTION ENGINES.

1,349,516.

Specification of Letters Patent. Patented Aug. 10, 1920.

Application filed May 23, 1919. Serial No. 299,368.

To all whom it may concern:

Be it known that I, GERARD JOHAN LUGT, subject of the Queen of the Netherlands, and residing at Amsterdam, Netherlands, have 5 invented certain new and useful Improvements in Devices for Supplying Cooling Liquids to Pistons of Internal-Combustion Engines, of which the following is a specification.

- 10 The present invention relates to a device for supplying a cooling liquid to the piston of an internal combustion engine consisting of a dipping tube affixed to the piston and provided with means for rendering its resistance as a liquid conduit greater in one sense of the flow than in the other and a stationary tube arranged underneath the piston and acting as a liquid receptacle from which the liquid is transmitted to the piston 15 by the dynamic energy of the same.

The dipping tube of the known devices of this kind plunges at each downward stroke with great velocity into the liquid of the wider stationary tube: in order to prevent the liquid from splashing out of the latter tube it is therefore necessary to provide the tube with a simple stuffing-box which although it does not require to be tight against pressure has the drawback of giving trouble 20 when the dipping tube is not in perfect alignment with the stationary tube.

According to the present invention this drawback is avoided by providing the stationary tube in which the dipping tube 25 moves up and down with a narrower inner tube which permanently delivers the cooling liquid laterally into the wider tube. At each downward stroke the lower part of the dipping tube thus receives a certain quantity 30 of cooling liquid leaving the inner stationary tube, this liquid being transmitted to the piston in consequence of the special shape of the dipping tube in consequence of the provision of baffle plates or equivalent means 35 rendering its resistance as a liquid conduit in one sense of the flow greater than in the other. The superfluous cooling liquid flows away through the outer stationary tube, the latter acting therefore simply as a receiver 40 for the overflowing liquid without that it is filled with liquid to a certain level as in

ordinary cases, any splashing being thus prevented.

In the accompanying drawing Figure 1 represents diagrammatically a device according to the invention, Fig. 2 the upper end of the inner liquid supply tube.

In Fig. 1 the hollow piston is indicated by 1, the dipping tube by 2. This tube as shown by the drawing is provided with baffle plates and a mouth piece in form of a nozzle. The liquid supply conduit 7 is arranged within the wider stationary tube 3 provided with a liquid outlet conduit 6. At its upper end the liquid supply tube is closed (Fig. 2) while it is provided near this end with lateral outlet openings 8.

Having now described my invention I declare that what I claim is:

1. In a piston cooling mechanism, the combination of a stationary tube having a water inlet, a reciprocating hollow piston, a tube carried by said piston, and having an open end discharging into said piston, the lower end of the tube having a vertical flange spaced from the tubular walls to form a pocket, the flange also forming a restricted opening, baffles in said tube between the discharging and restricted ends thereof, and a water inlet tube loosely telescoping the restricted end of said reciprocating tube, and having a closed end provided with water discharging openings, the water accumulating in the pocket, and the excess thereof passing through the space between the water inlet tube, and the flange, the water in the pocket being vertically lifted by momentum to the baffles, and eventually discharged into the piston.

2. In a piston cooling mechanism, the combination of a stationary tube having a water inlet, a reciprocating hollow piston, a tube carried by said piston, and having an open end discharging into said piston, the lower end of the tube having a vertical flange spaced from the tubular walls to form a pocket, the flange also forming a restricted opening, baffles in said tube between the discharging and restricted ends thereof, and a water inlet tube loosely telescoping the restricted end of said reciprocating tube, and having a closed end, from which depends a

conical lug to spread the water passing through the tube, through openings formed in said tube adjacent said conical lug, the water accumulating in the pocket, the excess water passing through the space between the water inlet tube and the flange, the water in the pocket being vertically

lifted by momentum to the baffles and discharged into the piston.

In testimony whereof I affix my signature. 10
GERARD JOHAN LUGT.
